Robert Burns

attorney.

ATTEST:

W. J. Stewart

W. J. Murphy

UNITED STATES PATENT OFFICE.

WELLS GOODHUE, OF CHICAGO, ILLINOIS, ASSIGNOR OF ONE-HALF TO
GEORGE J. ADAMS, OF SAME PLACE.

AUTOMATIC INDICATOR.

SPECIFICATION forming part of Letters Patent No. 369,639, dated September 6, 1887.

Application filed March 9, 1887. Serial No. 230,314. (No model.)

To all whom it may concern:

Be it known that I, WELLS GOODHUE, a citizen of the United States, and a resident of Chicago, in the county of Cook and State of Illinois, have invented a certain new and useful Improved Automatic Indicator; and I do hereby declare the following to be a full, clear, and exact description of the same, reference being had to the accompanying drawings, forming a part of this specification.

This invention relates to mechanism for use on doors and other like articles for giving an indication of the engagement or disengagement of the party occupying the room to the door of which said mechanism is applied; and the object of the present invention is mainly to provide an automatically-acting device for operating a suitable indicating or other mechanism attached to the door, and which will indicate when the person using the room is engaged. I attain such object by mechanism essentially as shown in the accompanying drawings, in which—

Figure 1 is an elevation, partly sectionized, showing my invention adapted to the door of a room; Fig. 2, a horizontal section of the same. Figs. 3 and 4 are detail views of modified forms of my invention, and Fig. 5 a detail horizontal section of another modified form of the same.

Similar letters of reference indicate like parts in the several views.

Referring to the drawings, A represents a central portion of a door, and B the frame or jamb of the same.

C is the name-plate inserted in the door, as shown, and carrying in addition to the name of the occupant of the office a suitable legend or notice—such, for instance, as the word “engaged”—such notice or legend being adapted to be covered or hid, when the party is disengaged, by means of the following mechanism:

D is a plate preferably arranged to move in a vertical direction in front of said notice or legend and receiving motion from a bell-crank lever, E, which in turn is operated by a spring-bolt, F, arranged horizontally in the door, as shown, with its free end adapted to bear against the jamb B of the door on the side adjacent to the hinges of the same, so that the closing of the door will tend to automatically force said bolt inwardly against its operating-spring F',

the tendency of which spring is to push said bolt outward. The pushing in of said bolt will, through the bell-crank lever E, force the plate D downward and expose the legend or notice to view. The end of the spring-bolt is made adjustable in the shape of a button, f, screwing upon said end and forming an abutment for one end of the operating-spring F'. The purpose of this construction is to admit of such button screwing in flush with the edge of the door, so as to render the indicating mechanism inoperative when required.

The housing F² for the end of the spring-bolt will be of a cup-shape to admit of the ready adjustment of the button f. As modifications of my improvement, the plate D may form an integral part of the bell-crank lever E, as indicated in Fig. 3. Again, such plate may be arranged to slide horizontally instead of vertically, as before described, without departing from the spirit of my invention, as indicated in Fig. 4; or, the plate D may be so modified as to have a turning instead of a lifting motion, in which case it would be of a circular or sector shape, as indicated in Fig. 5.

I claim—

1. In an automatic indicator for use on doors, the combination of a spring-bolt the free end of which contacts with the jamb of the door adjacent to the hinges, and an indicating-plate connected to and actuated by the spring-bolt in manner substantially as herein described, and for the purpose set forth.

2. In an automatic indicator for use on doors, the combination of a spring-bolt the free end of which contacts with the jamb of the door and is provided with an adjustable button, f, with an indicating-plate connected to and actuated by the spring-bolt in manner substantially as herein described, and for the purpose set forth.

3. The combination of plate D, bell-crank lever E, and spring-bolt F, with the door A and jamb B, the parts being arranged and adapted to operate in manner substantially as herein described.

In testimony whereof witness my hand this 5th day of March, 1887.

WELLS GOODHUE

In presence of—

GEO. J. ADAM,
ROBT. BURNS.
